CECIL J. SWAIM, OF MONTREAL, QUEBEC, CANADA.

RIBBON MECHANISM.

1,278,252.

Specification of Letters Patent. Patented Sept. 10, 1918.

Application filed March 9, 1916. Serial No. 83,083.

To all whom it may concern:

Be it known that I, CECIL J. SWAIM, a citizen of the United States of America, and resident of the city of Montreal, in the 5 Province of Quebec and Dominion of Canada, have invented certain new and useful Improvements in Ribbon Mechanism, of which the following is a full, clear, and exact description of the invention.

10 This invention relates to improvements in ribbon mechanism for typewriters, and the object of the invention is to provide a supplementary ribbon mechanism attachable to a typewriter to provide the same with any 15 desired number of additional ribbons, for the purpose of replacing carbon paper when it is desired to make a number of copies at a single writing.

A further object of the invention is to 20 provide a supplementary ribbon mechanism which may be instantly moved into or out of operative position.

A still further object is to provide a ribbon mechanism applicable to practically all 25 makes of typewriters.

Another object is to provide a supplementary ribbon mechanism which will permit use of the full width of the typewriter platen.

30 Still another object is to provide means for satisfactorily employing a number of ribbons in superposed relation, and for maintaining such ribbons separated and in perfect register.

35 It will be readily understood that owing to the numerous variations in the structure of different makes of typewriters and the constant production of new models having unforeseeable variations of structure, it is 40 impossible within the bounds of practicability to illustrate and describe an attachment which will be applicable to every make of typewriter. Such alterations in the structure hereafter described, as may be necessary to adapt the structure to any particular make of typewriter, must therefore be considered as modifications which fall within the limits of the present invention.

The device consists of a light framework 50 adapted to rest on the carriage of a typewriter and to be releasably connected thereto. The framework is provided with a pair of ribbon spool holders arranged one at each end of the carriage either axially parallel with or axially transverse to the type-

writer platen as may be desired. These spools carry a plurality of ribbons which are guided by suitable means across the platen in superposed relation. The means for guiding and separating the ribbons is 60 of great importance, and comprises a plate bent back and forth upon itself to form a plurality of separate ribbon passages.

The use of such a ribbon mechanism as hereafter described is particularly essential 65 in typewriters provided with paper roll holding attachments, and the invention has therefore been illustrated as operating in conjunction with such a device.

In the drawings which illustrate the invention:—

Figure 1 is a side elevation of a ribbon mechanism showing the same flexibly secured to a fragment of a paper roll holding attachment. 75

Fig. 2 is a front elevation of the structure shown in Fig. 1.

Figs. 3 and 4 are sections on the lines 3—3 and 4—4 respectively, Fig. 1.

Fig. 5 is a plan view of a ribbon spool 80 spindle.

Fig. 6 is a side elevation of a slightly different form of device.

Fig. 7 is a front elevation of the structure shown in Fig. 6, having parts broken away. 85

Fig. 8 is a sectional view of a slightly alternative form of ribbon guide.

Referring more particularly to the drawings, 11 designates the platen of a typewriter having a spindle 12, and 13 designates a 90 portion of the typewriter carriage having a back stay 14. In certain makes of typewriters, the platen is mounted in a basket which shifts within the carriage for the purpose of changing from lower to upper case letters 95 and vice versa. The stay rod of such a carriage is indicated at 15. The driving arm of a paper roll holding attachment is shown at 16 as hooked to the carriage back stay 14, for the purpose of imparting carriage movement to the roll holding attachment. This arm carries a post 17 having a rod 18 extending parallel with the platen, and forming a guide over which the paper passes to the platen. 100

The ribbon mechanism comprises a pair of end frames 19 adapted to lie against adjacent surfaces of the carriage portions 13, and having outwardly turned feet 20 resting on the carriage portions 13. These end 110

frames are provided with notches 21 adapted to engage the platen basket stay 15, so that the ribbon mechanism will follow the platen in all its movements. These end frames are connected by links 22 with the standards 17, the connection between the frames and links preferably including a slot 23 in which the connecting pivot 24 may operate. This is for the purpose of allowing the ribbon mechanism to adjust itself perfectly to the carriage, and also to permit the entire mechanism to be swung upwardly and rearwardly out of the way, as indicated in dot and dash lines, Fig. 1. When in such position, a notch 25 in each frame engages the platen basket stay 15. The pivot member 24 may if desired be continuous between the frames 19 for the purpose of stiffening the mechanism and forming a connection between the ends thereof independent of that obtained through the paper roll holding attachment. The forward ends of the frames are connected by a transverse member 26, one edge of which may be also used as a knife against which paper may be torn off in suitable lengths.

A spool holder 27 is mounted on each end frame, and is of U-shape, as shown in Fig. 1, each arm being bifurcated at its extremity, as shown in Fig. 2. The arms are turned so as to hold the ribbon spools 28 clear of the ends of the platen, as clearly illustrated in Fig. 2. The inclined position of the holders naturally indicates an inclined position of the slots 29 formed between the bifurcations. As will be readily seen, this inclination of the slots is away from the pull of the ribbon passing across the platen, so that nothing beyond the force of gravity and the pull of the ribbons is required to hold the spools in position. Each spool holder includes a spindle 30 revoluble in the slots 29. This spindle carries a ratchet wheel 31 adapted for coöperation with any suitable pawl forming part of a driving or holding mechanism. The ratchet wheel is also provided with a pin 32 adapted to engage the eccentrically disposed opening found in all ribbon spools, for the purpose of revolubly connecting same with the ribbon feed mechanism of the typewriter on which they are used. It will thus be seen that spools of the ordinary description may be used, the spindles being passed through the spool and the pin 32 engaged therein. The spindle is then dropped into the slots 29 and the ratchet wheel meshes with whatever spool controlling mechanism is provided, such as the pawl shown in Fig. 2.

For the purpose of guiding the ribbons across the platen at the printing line, guides 33 are provided on each end frame. These guides preferably take the form of a sheet of thin, suitably stiff metal bent back and forth upon itself to form a series of pas-

sages or very deep narrow grooves 34 for the individual ribbons. As will be readily seen, the spools are necessarily in such position that the ribbons cannot be passed between the spools in the printing line, and it is therefore necessary to turn the ribbons so as to bring a part of the ribbons between the spools in the printing line. This is accomplished by forming the free ends of the guides at an angle of 45°, as clearly shown in Fig. 1. For many years past, many endeavors have been made to produce a satisfactory multiple ribbon mechanism for typewriters. All those working along this line have met with the difficulty of separating the ribbons in order to prevent a tight ribbon dragging and bunching a slack ribbon, and also with the difficulty of maintaining the ribbons in superposed relation after turning them across the platen. When only two or three ribbons are used, the faulty register is not of very great importance, as there will be sufficient width of ribbon available at the printing line. When, however, a large number of ribbons is used, this factor has presented an apparently insurmountable difficulty. The ribbon guide shown herein is, however, of such nature that any number of ribbons may be used, and all will be maintained in perfect register and sufficiently separated to completely preclude the possibility of one ribbon dragging another. As will be seen, the end of the guide 33 is slightly notched or set back where the ribbon passes, so that projections 35 are formed providing ribbon guides. In the front edge of the guide, a similar recess 36 is formed by cutting through the metal at the bend. This cut does not extend transversely of the guide, but is slightly stepped, as shown in Fig. 4, so that the ribbons are separated.

The ribbons, which may be three in number for the guide shown, pass from the spools through the two passages of the guide, and one over the inner surface. At the inclined bottom of the guide, the ribbon traveling over the inner surface is turned around the inclined edge, and through the first passage, emerging at the front vertical edge. The ribbon in the first passage is turned around the inclined edge and through the second passage, and the ribbon in the second passage is similarly turned over the edge and travels against the outer surface of the guide. It will be readily seen that the ribbons are now traveling in a forward direction at right angles to the platen. The ribbons are now turned over the front edge of the guide through an angle of 90°, so as to travel across the front of the platen. It is in the notched portion 36 of this front edge that the stepping previously referred to occurs. The edges are progressively set back from the outer layer

to the inner, as clearly shown in Fig. 4, thus separating the ribbons for their passage across the platen. The feature essential to keeping the superposed ribbons exactly in register is the provision of the inclined edges over which they turn all in the same inclined plane, and not in a series of parallel inclined planes, as has been previously done.

10 The form shown in Figs. 6 and 7 illustrates a slightly different arrangement of the invention applicable to a different style of typewriter from that shown in Figs. 1 and 2. These latter figures also illustrate 15 the spools arranged axially parallel with the platen and the ribbon mechanism mounted independently of any mechanism other than the typewriter. In this adaptation of the invention, the carriage side members 19^a, instead of being supported on the platen basket or other portion of the carriage, are provided with notches 37 which engage the platen spindle, so that the ribbon frame is supported directly on the 20 platen, and will follow its movements in the same manner as already described. A second point of support is necessary, and this may be obtained by providing a slotted rearward extension 38 of the side frames 25 adapted to engage the carriage stay 14 or other suitable part of the machine, the slot of this extension being of such form that movement of the platen is not interfered with. This slot and the side frames themselves 30 may in fact be formed so that a single design of ribbon mechanism will be applicable to a number of makes of typewriters. The spool holders and spools with their attendant mechanism are substantially 35 as previously described, with the exception that they are turned into axially parallel relation with the platen. This turning of the spools necessitates a turning of the ribbon guides 33, but beyond the change of 40 position, there is no necessary change in the ribbon guides. The ribbons, when threaded through the guide, in place of being turned over the vertical edge thereof, continue 45 straight across the platen in the plane of the guides. A further slight modification, 50 which is found to be advisable with certain makes of typewriters, is also illustrated, and consists in mounting the tearing off 55 knife 26^a at the free ends of arms 39, which are pivoted at their opposite ends to some suitable portion of the frames, so that the knife may be swung upwardly and rearwardly to the position shown in dot and dash lines, where it will not interfere with 60 the threading of paper between the ribbons or the correction of errors which have been made in the writing. The ends of the cutting off knife may project laterally, as at 65 40, to support the knife on the side frames, or if desired, the knife may be supported

merely by the arms 39 resting on a transverse stay 41, or any other suitable support carried by the frames.

Each of the forms shown has its advantages. The arrangement of spools in Figs. 1 and 2 permits the positioning of the ribbon guides at the ends of the platen, so that the entire width of the platen is available for writing. The form shown in Figs. 5 and 6 is neater and more compact as regards the arrangement of ribbon spools, but in the majority of typewriters, the ribbon guides will encroach to a certain extent on the ends of the platen, thus reducing the available writing space. The link 22 of Fig. 1 may obviously be omitted, so that the ribbon mechanism can be removed from the typewriter in an instant of time in exactly the same manner as the form shown in Fig. 6. Conversely, the latter form may, if desired, have a link or other connection with a paper roll holding attachment. In the same way, the swing-up tearing off knife shown in the latter embodiment may be applied to the former. It will be seen that with both forms, the mechanism merely rests upon the typewriter carriage, and may be separated therefrom at will by a simple lifting movement, thus enabling the multiple ribbon mechanism to be thrown out of operation at a moment's notice and the typewriter used for ordinary work. No ribbon shifting mechanism has been shown, as for many purposes, it has been found quite satisfactory to shift the ribbons by hand when required. This is rendered possible by the fact that the exposed length of ribbon travels with the platen, so that each letter space on the ribbons is only struck by the type once in each line of writing.

In Fig. 8, a slightly different construction of ribbon guide is shown, and consists of a number of similar separate plates 42 of suitable shape, connected together with fillers 43 therebetween by means of rivets 44.

Having thus described my invention, what I claim is:—

1. In a multiple ribbon mechanism, a ribbon guide comprising a sheet of material bent back and forth on itself and forming a series of separate ribbon passages, said guide having the lower end thereof inclined to its edges.

2. In a multiple ribbon mechanism, a ribbon guide having a plurality of separate ribbon passages therein, and ribbon turning members at the lower ends of said passages arranged all in the same inclined plane.

3. In a multiple ribbon mechanism, a ribbon guide having a plurality of separate ribbon passages therein, and ribbon turning means carried by said guide arranged to turn the ribbons in the plane which they occupy in the guide and maintain the ribbons in register.

4. In a multiple ribbon mechanism, a ribbon guide having a plurality of separate ribbon passages, means for turning said ribbons in their normal plane and maintaining them in register, and means for turning the ribbons out of their normal plane and maintaining them separated.
5. In a ribbon mechanism, a ribbon guide having a plurality of separate ribbon passages therein, inclined end edges on said guide arranged to turn the ribbons, and a ribbon outlet in the front edge of said guide exposing the edges of the ribbon passage separating walls, said edges being stepped back from one side of the guide to the other.
6. In a multiple ribbon mechanism, a framework adapted to rest on the carriage of a typewriter, including normally fixed anchor members engageable with the car-

riage frame, a ribbon spool carrying frame, 20 a link connection between said spool frame and the anchor members permitting sliding and pivotal movement of the spool frame, said spool frame having feet adapted to support it on the carriage frame in operative 25 position, and end members adapted to impart carriage movement to the spool frame, said spool frame having notches therein adapted to receive the carriage frame to releasably hold the spool frame in operative 30 and inoperative positions.

In witness whereof, I have hereunto set my hand, in presence of two witnesses.

CECIL J. SWAIM.
